US0D1108529S

(12) **United States Design Patent** (10) **Patent No.:** **US D1,108,529 S**
(45) **Date of Patent:** **** Jan. 6, 2026**

(54) **CAMERA**

- (71) Applicant: **Blackmagic Design Pty Ltd**, South Melbourne (AU)
- (72) Inventors: **Grant David Petty**, South Melbourne (AU); **Simon Milne Kidd**, South Melbourne (AU); **Stuart Damian Elford**, South Melbourne (AU); **Shannon Howard Smith**, South Melbourne (AU); **Michael William John Cornish**, South Melbourne (AU); **Ryan Harper**, South Melbourne (AU); **Adam Scott**, South Melbourne (AU); **Edward Truong**, South Melbourne (AU); **Michael David Hooks**, South Melbourne (AU); **Oliver Andrew Charles Whittaker**, South Melbourne (AU); **Diarmuid Padraig Whittle**, South Melbourne (AU)
- (73) Assignee: **Blackmagic Design Pty Ltd**, South Melbourne (AU)
- (**) Term: **15 Years**
- (21) Appl. No.: **29/966,915**
- (22) Filed: **Oct. 7, 2024**

(30) **Foreign Application Priority Data**

- Apr. 8, 2024 (AU) 202412145

(57) **CLAIM**

The ornamental design for camera as shown and described.

DESCRIPTION

FIG. 1 is a front perspective view of a camera.

FIG. 2 is a top plan view thereof.

FIG. 3 is a bottom plan view thereof.

FIG. 4 is a front side elevation view thereof.

FIG. 5 is a back side elevation view thereof.

FIG. 6 is a left side elevation view thereof.

FIG. 7 is a right side elevation view thereof; and,

FIG. 8 is a rear perspective view thereof.

The features shown in broken lines in the drawing depict portions of the camera and form no part of the claimed design.

1 Claim, 8 Drawing Sheets
